PORTABLE RECEPTACLE

Abraham Halpin, New York, N. Y.

Application December 21, 1936, Serial No. 116,884

7 Claims. (Cl. 150—1.5)

This invention relates to devices such as portable receptacles.

One object of the invention is to provide a device of the character described having a pocket for concealing a slideable handle for the receptacle, coordinated in an improved manner so as to obtain a diminished thickness of the wall structure, which is of importance especially in a brief case.

Another object of the invention is to furnish a device of the type mentioned wherein an improved pocket structure provides a mouth portion acting as a guide for the handle slideable thereinto to diminish wearing and fraying of the edge of the mouth.

Another object of the invention is to construct a device of the species alluded to wherein the handle is quite rigidly held in its concealed position in a pocket, and the latter is secured against relative distortion of the walls of the pocket, so that a neat appearance is maintained even after long use.

Another object of the invention is to furnish an improved handle and pocket therefor, wherein the pocket is partially closed but with the mouth thereof free to receive the handle.

Another object of the invention is the provision of a portable receptacle having a pocket and a handle slideable therein having end flexible arm portions to flex with the wall of the receptacle, and the handle having at its end a stop portion guided into secure, nontwisting engagement with a portion of the pocket, whereby relatively long arms can be used for the otherwise rigid handle, to thus permit the receptacle to be conveniently carried.

An important object of the invention is to provide a device as set forth wherein a concealable handle is furnished, the arrangement permitting guiding action for the handle into and out of its pocket without the use of straps or the like, and being very simple and inexpensive to manufacture, and durable, reliable and efficient in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a view in elevation showing a de-

vice embodying the invention, with the handles in the concealed position.

Fig. 2 is a similar view with the handles in receptacle carrying position.

Fig. 3 is a sectional view taken on the line 5—3 of Fig. 1.

Fig. 4 is an enlarged fragmentary sectional view taken on the line 4—4 of Fig. 2.

Fig. 5 is an enlarged view in elevation of a handle.

Figs. 6 and 7 are sectional views taken on the lines 6—6 and 7—7, respectively, of Fig. 5.

Fig. 8 is an enlarged sectional view taken on the line 8—8 of Fig. 2.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 10 denotes a device such as a portable receptacle, and particularly a brief case embodying the invention. The same may include a main compartment 11 provided by the side walls 12 and which is open at the top, said opening being closable as by a slide fastener 14. Each side wall may have a slot or slit 15 spaced below and extending along the edge or opening at the slide fastener 14 for a purpose hereinafter described.

Disposed within the compartment 11 and secured to the inner face of each wall 12, is a wall portion 16 which may be stitched to the wall 12 as by a line of stitching 17 which extends over the slit 15 to thus afford a pocket P whose mouth is at 15, and which is otherwise closed. A fastening means such as a line of stitching 18 may be disposed along a line generally parallel to the slit 15 to interconnect the wall portions 12 and 16 to thus divide the pocket P into an upper pocket portion P1 and a lower pocket portion P2. If it be desired to slightly space the wall portions 12 and 16 away from each other, a filler strip 19 may be disposed between the wall portions with the stitching 18 passing through said strip. The elements 18 and 19 may be arranged to permit intercommunication between the upper and lower pocket portions and hence may terminate in spaced relation to the ends of the pocket P to thus afford passages 21 between the

said elements and the stitching 17. All materials used may be flexible to yield with the normal use of the receptacle.

U-shaped handles 22 may be employed at each side wall 12 for carrying the receptacle, each handle having a top portion 23 and arms 24 to provide a balanced support. The handles may be rigid throughout, except that the lower portions 25 of the arms may be flexible to yield with the wall structure of the receptacle. The portions 25 may have securing portions extending laterally or in opposite directions in the plane of the handle, as embodied, for instance, in a strip member 26 interconnecting the lower ends of each handle.

The handle 22 is disposable in a pocket P so that the upper handle portion 23 lies in the upper pocket portion P1. For this reason, the line of stitching 18 is spaced sufficiently from the slit 15. Sufficient space may be provided to permit the use of a closure, such as a snap fastener 27 to close the upper pocket portion above the handle. The arms 24 extend through the passages 21 into the lower pocket portion P2, in which lies the strip 26 in position to have stop engagement with the stitching 18 upon upward movement of the handle into carrying position as shown in Fig. 2.

The handle 22 may consist of a wire reinforcement 28 of U-shape form, about which is secured a strip of material to form a sleeve 29 for the wire. Where the wire terminates at 30, the sleeve 29 is slotted to lie flat and thin to form the flexible portion 25, to which the strip 26 may be secured by a rivet 31.

It will be understood that the handle and pocket structures are identical for both sides of the device 10.

In manufacture, the walls 12, lying in a plane may have the strips 19 glued thereto, then the handles are placed, and the wall elements sewed down at 17 and 18 to the walls 12 which have been previously slotted at 15. The receptacle is then completed in the usual manner.

In use, the pockets P are always kept partially closed by the fastening means 18, which saves distortion thereof. Also fraying of the mouth of the pocket at 15 by sliding movement of the handle is avoided, because the entire pocket portion P1 acts as a guide for the handle, and the lower edge at 15 is free to move away from the handle, while the latter is restrained against outward swinging movement. The structure is very neat, thin and compact and the handle is securely held in the concealed position, even without the closure 21. While the arms 24 of the handle are relatively long, the parts 25 afford flexibility. The strip 26 is guided and retained flat along the plane of the pocket by the drawing together of the pocket at the stitching 18, irrespective of the flexibility of the handle portion 25.

A very important advantage is that the cost of manufacture is greatly reduced, the operations being well adapted to quantity production.

There is thus afforded a novelty case which fulfills the objects of the invention, and may be held under the arm with the handles concealed, or carried by means of the handles at the convenience of the user.

I claim:

1. A device including a portable receptacle having side walls providing therebetween a main compartment open at an upper edge of the receptacle, wall sections within the compartment in relative proximity to said edge and marginally individually secured to said walls, the latter having slits extending along and in relative prox-

imity to said opening so as to afford downward opening pockets with the wall sections, U-shaped handles for the receptacle disposed so as to be slidable through said slits into the pockets to be housed therein and outward of the pockets so as to project above said edge for carrying the receptacle, said handles having the lower portions of their respective arms retained in the pockets in the receptacle carrying position of the handles, and each of the pockets having a fastening means interconnecting the wall sections and their respective walls, each fastening means being spaced downward away from the slit and being spaced from the said marginal securing of the wall sections, each fastening means extending along a line parallel to the slit and providing beyond the ends thereof passages for the handle arms and dividing its pocket into upper and lower pocket portions, the upper pocket portion serving as a guide for the handle arms, the handle arms having lower end portions having stop engagement with the fastening means when the handle is slid outward of the pocket and being otherwise free of the fastening means, the arms of each handle being received in a lower pocket portion and the upper part of the handle in an upper pocket portion when the handle is housed in the pocket, said fastening means thus preventing spreading of the pockets by the handles and maintaining the latter in fixed position when housed in the pockets, and releasable closure means at the slits for closing the upper pocket portions.

2. A device including a portable receptacle having a side wall, a U-shaped handle for the receptacle, a wall portion cooperating with said wall to provide a pocket having an elongated top opening, the handle being disposed so as to be slidable into housed position in the pocket and outward of the opening for carrying the receptacle, means interconnecting the wall and wall portion in spaced relation to said opening to divide the pocket into upper and lower portions, said means being spaced from the ends of the pocket to provide passages for the arms of the handle, and the arms having end portions in the lower pocket portion adapted for stop engagement with the said means upon moving the handle into carrying position, and the upper portion of the handle being snugly retained in the upper pocket portion upon movement of the handle in the housed position in the pocket, the upper pocket portion being closed at its ends and serving as a guide for the handle arms, said closed ends being in relatively close proximity to the handle arms.

3. A device including a portable receptacle having a main compartment, said receptacle having a plurality of wall portions providing a pocket having an elongated top opening on the outside of the receptacle, a U-shaped handle for the receptacle movable into the pocket, means extending generally parallel to the pocket opening and interconnecting the said wall portions, said means being so spaced downward of the pocket opening as to afford an upper pocket portion for housing the upper part of the handle, said means cooperating with the pocket to afford passages for the arms of the handle into the lower part of the pocket, said arms having means adapted for stop engagement with the first named means upon upward movement of the top handle portion out of said pocket opening into receptacle carrying position.

4. A device including a portable receptacle

having a main compartment, said receptacle having a wall structure of flexible material for said compartment, said wall structure comprising a plurality of wall portions affording a pocket, the latter having an elongated top opening disposed in proximity to an edge of the receptacle, a U-shaped handle adapted to be housed in the pocket, means interconnecting the wall portions of the latter at points parallel to and spaced from the pocket opening so as to afford a top pocket portion adapted to snugly receive the upper part of the handle, the upper pocket portion serving as a relatively snug fitting guide for the handle, said means affording openings for movement of the arms of the handle into the lower part of the pocket, the lower portions of said arms being flexible so as to yield with the wall structure, and stop portions at the lower ends of said arms and being spaced below said means to have stop engagement therewith upon upward movement of the handle outward of the pocket into receptacle carrying position.

5. A device including a portable receptacle having a main compartment, said receptacle having a wall structure of flexible material for said compartment, said wall structure comprising a plurality of wall portions affording a pocket, the latter having an elongated top opening disposed in proximity to an edge of the receptacle, 10 a U-shaped handle adapted to be housed in the pocket, a line of stitching interconnecting the wall portions in spaced relation to the ends of the pocket and in spaced relation to the pocket opening, said line of stitching holding the wall 15 portions in close relation to each other, the upper part of the handle being received in the pocket above the line of stitching, the arms of the handle extending into the portion of the pocket below the line of stitching between the ends of the latter and the ends of the pocket, said handle being relatively stiff except that the end portions 20 of the handle are flexible to yield with the wall structure, and a strip element interconnecting the ends of the handle, said element being thin 25 and lying flatwise along the plane of the pocket

to be guided into edgewise stop engagement with the line of stitching by the closely related adjacent wall portions upon movement of the upper part of the handle out of the pocket for carrying the receptacle.

6. A device including a portable receptacle having a compartment having a top opening and a flexible side wall for said compartment, a wall section disposed in the compartment and connected to the side wall, the latter having a 10 slit extending along said top opening to afford a pocket with the wall section, a U-shaped handle adapted to be housed in the pocket, a fastening means interconnecting the wall and the wall section in spaced relation to said slit to afford 15 an upper pocket portion for receiving the upper part of the handle, the fastening means extending between the arms of the handle and being spaced from the ends of the pocket, the handle being rigid and having the lower end portions 20 of its arms flexible, a strip element interconnecting the lower ends of the arms and disposed below the fastening means, said handle being movable outward of the pocket into receptacle carrying position with the strip element having stop 25 engagement with the fastening means.

7. A device including a portable receptacle having a compartment and a wall therefor, said wall comprising a plurality of wall portions affording an upward opening pocket, a handle of 30 U-shaped movable into the pocket, the arms of the handle having laterally extending free end portions, and the pocket including means interconnecting the wall portions inward of the ends of the pocket and intermediate of the said opening and bottom of the pocket for stop engagement with the laterally engaging portions of the handles, to thus permit the handle to assume a position part way outside of the pocket for carrying the receptacle, and the top of the handle 35 being receivable in the pocket above the stop means with the pocket at the opening thereof serving as a relatively snug fitting guide for the handle arms.
